UNITED STATES PATENT OFFICE.

EVA M. COOKE, OF HORATIO, ARKANSAS, ASSIGNOR OF ONE-HALF TO CORA M. ROGERS, OF DALLAS, TEXAS.

WARDROBE.

Application filed December 10, 1923. Serial No. 679,716.

To all whom it may concern:

Be it known that I, Eva M. Cooke, a citizen of the United States, residing at Horatio, in the county of Sevier and State of 5 Arkansas, have invented a new and useful Wardrobe, of which the following is a specification.

This invention relates to furniture and more particularly to collapsible wardrobes.

10 The object of the invention is to provide a simple, strong, cheaply constructed article of this character which may be carried in a grip and when desired for use quickly opened up and mounted on a door or wall.

15 Another object is to provide a collapsible frame having detachable curtains which may be quickly applied or removed and when in use will completely house and protect garments against dust.

20 With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed without departing from the spirit of the invention.

25 In the accompanying drawings:—

Figure 1 represents a perspective view of a wardrobe constructed in accordance with this invention in position ready for use parts of the curtain being broken out to illustrate the interior.

30 Fig. 2 is a detail longitudinal section.

Fig. 3 is a transverse section taken on the line 3—3 of Fig. 2; and

35 Fig. 4 is a transverse section showing the frame collapsed, parts being broken out for convenience in illustration.

In the embodiment illustrated the wardrobe constituting this invention comprises a collapsible frame 1 composed of a body member 2 having foldable wings 3 and 4 mounted thereon and which are adapted to be opened up into the position shown in Fig. 1 when in use said wings being held in this position by means presently to be described.

40 The body member 2 is composed of spaced parallel bars 5 and 6 made angular in cross section as shown in Fig. 3 and are connected at their ends by cross bars 7 and 8 which are 45 preferably made integral therewith. The

top bar 5 is extended beyond the end bar 8 and is threaded at its terminal as shown at 9 to be screwed into a support. The lower bar 6 is also extended beyond the end bar 8 and has a downwardly and inwardly curved terminal 10 which is designed to abut a support into which the point 9 is screwed and form a brace for the frame so that it will be held securely against downward movement when clothing is hung on the bar 6.

45 The upper bar 5 is made round near its opposite ends with shoulders at the junction of said round portion 11 and the angular portion. These round portions of the bar 5 are designed to permit the wings 3 and 4 to pivot thereon when the device is to be collapsed. These wings are constructed exactly alike each being composed of a metal strap bent into substantially U-shape with the legs 12 and 13 thereof apertured at their terminals and threaded on bar 5 which is accomplished before said bar is welded to the end bar 8 or they may be applied in any other suitable manner. The legs of one wing lap those of the other as is shown 50 clearly in Fig. 1 and after being opened up into the position shown in said figure the apertured ends of said legs are moved along the bar 5 out of engagement with the round portions 11 thereof so that they will be securely held in this position.

55 A top curtain 14 is stretched over the outer faces of the wings 3 and 4 and secured to the end and side bars thereof in any suitable manner. Side curtains 15 are detachably connected with these wings by snap fasteners shown at 15 so that the curtains may be readily applied and removed. Suitable pockets 16 may be formed on the inner faces of the curtains to form containers for 60 shoes and similar articles.

65 An article constructed as herein shown and described may be conveniently carried in a trunk or grip and set up for use where desired being especially designed for travellers and campers.

70 I claim:—

75 An article of the class described comprising two parallel spaced bars, end bars rigidly connecting said parallel bars, one of the parallel bars having a longitudinal threaded extension at one end and the other a curved head to form an abutment, U-shaped wings having apertures in the free ends of the legs thereof which are mounted on one of 80

said parallel bars, latter bar having rounded portions near its ends for engagement by the ends of said wings to permit the wings to pivot freely upon said bar, the remainder 5 of the bars being polygonal in cross section so that when the apertured ends of said wings are engaged therewith the wings will be held in adjusted position.

In testimony that I claim the foregoing as my own, I have hereto affixed my signature in the presence of two witnesses.

MRS. EVA M. COOKE.

Witnesses:

Mrs. PERRY WADE,
J. H. WADE.
